(57) **CLAIM**

The ornamental design for a toy, as shown and described.

DESCRIPTION

FIG. 1 is a front perspective view of the present invention.

FIG. 2 is a top plan view of FIG. 1.

FIG. 3 is a front elevation view of FIG. 1.

FIG. 4 is a right side elevation view of FIG. 1, the left side
being a mirror image thereof.

FIG. 5 is a rear elevation view of FIG. 1; and,

FIG. 6 is a bottom plan view of FIG. 1.

Items shown in phantom-lines in FIGS. 1 to 6, are for illustrative purposes only to reflect the environment of the inventive design, and do not constitute a part of the claimed design.

1 Claim, 3 Drawing Sheets

FIG. 4

FIG. 3

FIG. 5

FIG. 6
